CLAIM

The ornamental design for a display screen with animated graphical user interface, as shown and described.

DESCRIPTION

FIG. 1 is a front view of a first image of a first embodiment of a display screen with animated graphical user interface showing the new design;

FIG. 2 is a front view of a second image of the first embodiment of FIG. 1;

FIG. 3 is a front view of a third image of the first embodiment of FIG. 1;

FIG. 4 is a front view of a first image of a second embodiment of a display screen with animated graphical user interface showing the new design;

FIG. 5 is a front view of a second image of the second embodiment of FIG. 4; and,

FIG. 6 is a front view of a third image of the second embodiment of FIG. 4.

The appearance of the image transitions between the images shown in FIGS. 1-3 and FIGS. 4-6. The process or period in which an image transitions to another image forms no part of the claimed design.

The broken lines of uneven length show the display screen and form no part of the claimed design. The broken lines of uneven length shown in the drawings illustrate portions of the display screen with animated graphical user interface that form no part of the claimed design.
